GAME BOARD

Erik Yngvar Iversby, Solliruta N-1720, Greaker, Norway

Filed Aug. 26, 1974, Ser. No. 500,736

Claims priority, application Norway Feb. 25, 1974

Term of patent 14 years

Int. Cl. D21—01

U.S. Cl. D34—5 SS

The single figure appearing in the drawing is a plan view of a game board according to my new design.

The game board according to my new design is of conventional thickness.

I claim:

The ornamental design for a game board, as shown and described.
